UNITED STATES PATENT OFFICE

2,450,454

BUFFING WHEEL

Sheldon S. Smith, Springfield, Mass.

Application September 18, 1947, Serial No. 774,794

2 Claims. (Cl. 51—193)

1.

My invention relates to improvements in buffing wheels and consists in the novel features, arrangement and combination of parts hereinafter described. The device of my invention is for use in polishing metals and other substances.

An object is to provide an improved wheel which is strong and durable and economical in its manufacture.

The wheel enables the employment in its construction of what has heretofore been practically waste material.

Flexible wheels have heretofore been made from a series of cotton discs placed against each other. These wheels when worn down through use are called "hubs" and are usually discarded.

The principal object of my invention is directed to the provision of a buffing wheel construction which is characterized by layers or circular rows of sections having relatively thick and thin portions with the sections being arranged whereby the buffing wheel has relatively thick and thin portions for more efficient buffing, cutting and abrading functions.

Another object is to provide a laminated buffing wheel which is built up from radially pleated units, the units being formed from a plurality of annularly cut blanks.

A still further object is to provide a device composed of units folded as indicated so as to provide pockets in the pleats between the plies which receive and hold the buffing compound and also form air ducts assisting in keeping the wheel cool.

The object of my invention is to provide a buffing wheel possessing superior qualities and having a firm central portion and a loose flexible peripheral portion, the body of the wheel being formed of two exterior discs, and a series of elements held therebetween.

With the foregoing and various other novel features and advantages and other objects of my invention as will become more apparent as the description proceeds, the invention consists in certain novel features of construction and in the combination and arrangement of parts as will be hereinafter more particularly pointed out in claims hereunto annexed and more fully described and referred to in connection with the accompanying drawings wherein:

Fig. 1 is a plan view of a buffing wheel embodying the novel features of the invention;

Fig. 2 is a diagrammatic edge view showing the relationship of certain sections in the wheel;

Fig. 3 is a plan view of one of the section forming elements of the wheel;

2

Figs. 4, 5 and 6 are plan views showing how the elements are folded to provide sections;

Fig. 7 is an end view of one of the elements in folded relation; and

Fig. 8 is a partial plan view showing a plurality of sections arranged in layer form.

Referring now to the drawings more in detail, the invention will be fully described.

An element 2 is shown in Fig. 3 which is in disc form and is made from fabric suitable for use in buffing wheels such as cotton or other filamentous material. Any number of such elements may be used.

The elements are folded upon themselves, as shown in Fig. 4 to provide a double thickness and are half circular, as shown.

Next, a portion of the element is folded over so that a portion 8 of two thicknesses overlies a portion 10 of two thicknesses as shown in Fig. 5. Finally, a portion 12 of four thicknesses overlies the portions 8 and 10 as shown in Fig. 6.

According to the folding method described, the element has a portion 12 at one side including eight thicknesses of material, a portion at the opposite side thereof including two thicknesses, and an intermediate portion including four thicknesses all as shown in Fig. 6.

If desired, the portion 12 of four thicknesses need not be folded again so as to overlie the portions 8 and 10 as described above.

The sections are disposed centrally of the wheel and are arranged in two superposed layers, each layer including circumferentially arranged sections. The portion 10 of one section of a layer is superposed on the thickest portion 12 of an adjacent section in the same layer.

The thickest portion 12 of the sections of one layer overlie the superposed thin and thick portions 10 and 12 of the layer of sections therebelow.

There may be as many layers of sections as desired and upper and lower end members such as 16 are provided at opposite sides of the superposed layers. Discs 16' serve as spacers between the upper and lower end members and between the layers.

The end members and sections of the layers are secured together by any suitable means such as by stitching indicated by 18 in Fig. 1 wherein lines of stitching extend transversely through the wheel and engage the component parts thereof.

Thus it will be seen that in the form shown, there are sufficient layers to provide alternating portions having 22 and 10 plies of material circumferentially spaced about the wheel. The

arrangement thus provides alternating thick and thin portions.

The assembled wheel shown in Fig. 1 is provided with a central arbor hole 20 which may be formed in the elements prior to forming into sections or it may be formed in the completed structure.

The wheel is clamped on an arbor by a clamping member in the usual manner and in such a way that it is rotated in the direction of the arrows in Figs. 1 and 8.

I have found that the arrangement of the sections as described provides relatively thick portions of the wheel which are spaced circumferentially of the wheel thereby to provide efficiency in abrading operations.

I have also found that by means of the wheel as arranged, more pulling power is provided since the wheel "grabs" more air than in loose buffers of the types heretofore known.

The buffer wheel of my invention provides a combination of cutting and polishing operations. The thickened portions perform a cutting operation and the thinned portions perform a polishing operation.

As the wheel is rotated in the direction of the arrows shown the portions of the sections are fanned out by action of air which keeps the wheel cool, whereby due to the thick or heavy portions the wheel has a rapid abrading action. In other words, the outer raw edges of the layers form the peripheral face of the wheel.

I have discovered, too, that the relatively thin and thick portions circumferentially of the wheel provide circumferentially spaced thick and relatively rigid peripheral portions during rotation of the wheel which are adapted for more rapid abrasive action than prior art wheels while at the same time the portions of the wheel fan out for rapid cooling. This is accomplished by the novel folding of the sections and the relative disposition thereof shown and described.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended

claims are therefore intended to be embraced therein.

What it is desired to claim and secure by Letters Patent of the United States is:

5 1. A buffering wheel comprising in combination, superposed and centrally secured together layers of circumferentially arranged flexible sections, each of said sections including a folded disc having a forward two ply portion with a forward 10 folded edge and an intermediate four ply section with a forward folded edge angularly and rearwardly disposed relative to the first edge and a rear eight ply portion with a forward folded edge angularly and rearwardly disposed relative to the 15 second-named edge, the two ply portions of the sections of each layer superposed on the eight ply portions of adjacent sections and the eight ply portions of the sections of one layer superposed over the corresponding portions of the sections 20 of the layer therebelow.

2. A buffering wheel for rotation in a certain direction comprising in combination, superposed secured together layers of circumferentially arranged disc-like flexible folded sections, each of 25 said sections folded to provide forward two ply intermediate and four ply and rear eight ply portions with each portion having a forward folded edge with the edges of the intermediate and rear 30 portions angularly and progressively rearwardly disposed relative to the forward edge of the two 35 ply portions, the intermediate, forward and rear portions of the sections adjacent the marginal edges thereof being unsecured and free for separating movements, the forward two ply portions 40 of the sections of each layer being superposed on the rear eight ply portions of the sections adjacent thereto and the eight ply portions and two ply portions of the sections of an upper layer disposed over the eight ply portions of the sections of the layer therebelow.
